UNITED STATES PATENT OFFICE.

WILLIAM JANSON ROCHE, OF COCHRANTON, PENNSYLVANIA, ASSIGNOR TO A. KIMBALL COMPANY, OF NEW YORK, N. Y., A CORPORATION OF NEW YORK.

PIN PRICE-TICKET.

1,250,662.

Specification of Letters Patent. Patented Dec. 18, 1917.

Application filed November 20, 1916. Serial No. 132,414.

To all whom it may concern:

Be it known that I, WILLIAM J. ROCHE, a citizen of the United States, residing at Cochranton, in the county of Crawford and State of Pennsylvania, have invented a new and useful Pin Price-Ticket, of which the following is a specification.

This invention has reference to pin price tickets, and its object is to provide a guard for the points of the wire used to attach the ticket to the goods.

The present invention has to do with a type of pin price tickets in which a wire staple pierces a portion of the ticket, and this staple is caused to pierce the goods, being afterward advanced so as to securely hold the ticket on the goods. Also the ticket is provided with a tab preventing the sharp ends of the pin or staple from catching in adjacent objects or piercing the hands of a person handling the goods.

With the present invention, there is provided a simple form of ticket made of a single piece of paper or cardboard folded upon itself and provided with a tab extension passed through an appropriate slot in the other end of the ticket, so that the tab telescopes with relation to the other end of the ticket. Attached to the tab is a staple-like pin so positioned that its points may be in part hidden and protected by the body of the ticket. The structure is of extreme simplicity and requires a minimum number of acts in its application to the goods, and in these particulars is superior to other pin tickets on the market.

The invention will be best understood from a consideration of the following detail description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings—

Figure 1 is a perspective view of the pin tab ticket complete and before folding.

Fig. 2 is a longitudinal central section through the ticket shown in Fig. 1.

Fig. 3 is a perspective view of the folded ticket ready for use.

Fig. 4 is a face view of the ticket applied to one edge of a piece of cloth.

Fig. 5 is a longitudinal section of the structure of Fig. 4.

Fig. 6 is a view similar to Fig. 5, but showing the application of the ticket to cloth at a point intermediate of the length of the cloth.

Fig. 7 is a perspective view of the ticket showing the position of the parts when the ticket is being manipulated to apply it to the cloth.

Referring to the drawings, there is shown a ticket 1 formed of a sheet of stout paper or cardboard, or other suitable material, usually made longer than wide and at one end formed into a longitudinally extended tab 2, narrower than the body of the ticket, while at the other end, which is of full width, there is produced through the ticket an elongated slot 3 extending transversely of the ticket.

The body 1 is folded at a point between the ends along a line substantially as indicated by the transverse dotted line 4, so that the body of the ticket is of double thickness because of the folding of the ticket upon itself. When so folded, the tab 2 is passed through the slot 3, so that the tab extends beyond that end of the ticket containing the slot 3. Where the tab 2 joins the body of the ticket rounded shoulders 5 are provided and all corners of the ticket may be rounded to avoid any part which may catch upon cloth or other articles.

There is also provided a staple 6, which may be a wire staple of the character usually employed in pin tickets, and this staple has a yoke end 7 bent about the free end of the tab 2 and provided with pointed legs 8 piercing the tab and then bent lengthwise of the tab toward the body of the ticket in spaced relation to the tab. The staple or pin is thereby securely fastened to the tab without liability of disconnection therefrom during the manipulation and use of the ticket.

The pin or staple 6 is so located with reference to the tab and the body of the ticket that when the tab is in traversing relation to the ticket through the slot 3, the pointed ends of the pin or staple may lodge through the slot 3 between the body of the ticket and the corresponding face of the tab 2.

In attaching the ticket, that portion of the

body of the ticket containing the slot 3 is forced toward the fold of the body portion by compressing the ticket lengthwise between the fingers of the user, so that the tab 5 2 is projected sufficiently to fully expose the pointed ends of the legs 8. These may then be readily threaded through the cloth, indicated at 9, so that the points of the pin or staple are exposed. If the ticket be applied 10 to the cloth near one edge of the latter, the exposed portions of the legs 8 may be on the opposite side of the cloth to that at which the legs enter, this being indicated in Figs. 4 and 5. If, however, it be desired to apply the ticket at some intermediate point 15 in the length of the cloth, the legs 8 are threaded through the cloth so as to enter the cloth at one face, pass through the cloth and then return through the cloth to the same 20 face, as indicated in Fig. 6. In either event the pointed ends of the pins are exposed without interference with the cloth in such manner that these pointed ends may be readily passed through the slot 3 and between the tab 2 and the corresponding face 25 of the body member, so that the pin points are effectively protected from accidental access. In this manner, the body of the ticket becomes a guard for the points of the pins behind which they are shielded by telescoping 30 through the slot 3 back of the body of the ticket and in front of the tab, considering the pins as being presented forwardly.

The application of the ticket is extremely 35 simple, requiring only the partial collapse of the ticket by pressure applied lengthwise thereof to expose the points of the pin or staple, and then the threading of the pins through the cloth, whereupon, by releasing the longitudinally applied pressure on the 40 ticket, it springs back to the original position and the points of the pin or staple move through the slot in the protected position. Because of the formation of the ticket there is no need of bending or clenching 45 the legs or prongs of the staple after they have pierced the cloth. In fact, the only operation needed is the compression of the ticket, the introduction of the legs or 50 prongs through the cloth and the release of the pressure on the ticket, these operations proceeding as one, thus permitting the application of the tickets to the cloth with extreme rapidity and with far greater rapidity than commercial forms of tickets for 55 the same purpose. Furthermore, the arrangement of the ticket and pin or staple permits the use of both faces of the ticket for notation and indicia.

60 What is claimed is:—

1. A pin price ticket comprising a sheet of suitable material folded intermediately upon itself, said ticket having a transverse slot at one end and a longitudinally extended tab at the other end, and a pin or staple

secured to the tab and having piercing means extending lengthwise of the tab toward the body of the ticket for lodgment between the tab and the body of the ticket with the tab and piercing portion of the pin 70 or staple extending through the slot.

2. A pin price ticket comprising a sheet of suitable material folded intermediately upon itself, said ticket having a transverse slot at one end and a longitudinally extended tab 75 at the other end, and a pin or staple having a portion folded about the free end of and secured to the tab and having piercing means extending lengthwise of the tab toward the body of the ticket for lodgment between the tab and the body of the ticket with the tab and piercing portion of the pin or staple extending through the slot.

3. A pin price ticket comprising an elongated strip of suitable material with a transverse slot adjacent to one end and with the other end formed into a longitudinally extended tab of a width to pass through the slot in a direction transverse of the length of the slot, and a pin or staple secured to the 85 tab at the end thereof remote from the body of the ticket and provided with piercing members extending lengthwise of the tab toward the body of the ticket whereby the tab with the staple thereon may be passed 90 through the slot.

4. A pin price ticket comprising an elongated strip of suitable material with a transverse slot adjacent to one end and with the other end formed into a longitudinally extended tab of a width to pass through the slot in a direction transverse of the length of the slot, and a pin or staple secured to the tab at the end thereof remote from the body of the ticket and provided with piercing members extending lengthwise of the tab toward the body of the ticket whereby the tab with the staple thereon may be passed through the slot, said pin or staple being of a length to have the piercing portions lodged between the tab and the body of the ticket when the tab is in traversing 100 relation to the slot to house and protect the piercing ends of the staple.

5. A pin price ticket comprising an elongated strip of suitable material with a transverse slot adjacent to one end and with the other end formed into a longitudinally extended tab of a width to pass through the slot in a direction transverse of the length 115 of the slot, and a pin or staple secured to the tab at the end thereof remote from the body of the ticket and provided with piercing members extending lengthwise of the tab toward the body of the ticket whereby the tab with the staple thereon may be passed through the slot, said pin or staple being of a length to have the piercing portions lodged between the tab and the body 120 of the ticket when the tab is in traversing relation to the slot to house and protect the piercing ends of the staple.

relation to the slot to house and protect the piercing ends of the staple, and the tab being of a length to permit the exposure of the piercing ends of the staple on collapsing the body of the ticket by pressure applied lengthwise thereto.

6. A pin price ticket comprising an elongated sheet of suitable material with a transverse slot at one end extending the major portion of the width of the ticket and a longitudinally extended tab projecting from the other end and of a width to pass through the slot, and a staple secured to the extremity of the tab and piercing the latter and having legs extending along the tab toward the body of the ticket, said legs being of a length to cause the housing of the free ends of the legs between the tab and the body of the ticket when the tab is in traversing relation to the slot.

7. A pin price ticket comprising a body member with a tab at one end with said body member folded intermediately upon itself and having the tab traversing the end of the body member remote from the tab, and a piercing member carried by the tab and extending along the latter toward the body of the ticket whereby the piercing member may be made to traverse the mate-

rial to which the ticket is to be attached and have the piercing part of the piercing member housed between the tab and the body of the ticket.

8. A pin price ticket comprising a body member with a tab at one end with said body member folded intermediately upon itself and having the tab traversing the end of the body member remote from the tab, and a piercing member carried by the tab and extending along the latter toward the body of the ticket whereby the piercing member may be made to traverse the material to which the ticket is to be attached and have the piercing part of the piercing member housed between the tab and the body of the ticket, said ticket also being yieldable lengthwise to cause relative movement between the tab and the body of the ticket for the exposure and retraction of the piercing portion of the piercing member.

In testimony that I claim the foregoing as my own, I have hereto affixed my signature in the presence of two witnesses.

WILLIAM JANSON ROCHE.
